CONTAINER FOR CAKES OR THE LIKE

James B. Swett, Barrington, R.I., assignor to Rexall Drug and Chemical Company, Los Angeles, Calif., a corporation of Delaware

Filed Nov. 15, 1965, Ser. No. 88,080

Term of patent 14 years

(Cl. D44—19)

FIG. 1

The dominant features of my design reside in the portions shown in full lines.

I claim:

The ornamental design for a container for cakes or the like, as shown and described.
